UNITED STATES PATENT OFFICE

2,642,637

LIQUID VAPORIZER

Vincenzo James Lee, Cleveland, Ohio

Application January 17, 1951, Serial No. 206,469

1 Claim. (Cl. 21—126)

1

This invention relates to vaporizers and particularly to a vaporizing attachment for vacuum cleaners.

This invention is a modification of the device disclosed in my co-pending patent application Serial Number 140,819, which was filed January 27, 1950, Patent Number 2,605,165, and entitled a "Vaporizing Attachment for a Vacuum Cleaner."

The principal objects of this invention are the same as those set forth in my other application but, however, this invention has the additional feature of being more efficient in its operation.

This invention also embodies a novel large capacity fluid holding device that is self-positioning within the containing structure. This is an improvement over my earlier invention which simply provided for a relatively thin absorption pad of limited capacity that required special positioning and retaining means.

These and other objects, as well as a fuller understanding of the invention, may be had by referring to the following description and claim together with the accompanying drawing in which like parts are designated by like reference characters and in which:

Figure 1 is a side elevation, partly in section, of the assembled vaporizer without the fluid reservoir;

Figure 2 is a view similar to that of Figure 1 but showing the fluid reservoir in place;

Figure 3 is a right end view of the same with portions broken away to show the inner structure;

Figure 4 is a front elevation of the fluid reservoir with a portion broken away;

Figure 5 is a right end view of the same;

Figure 6 is an expanded view of the device; and

Figure 7 is a side elevation, partly in section, showing the device mounted on an alternate type of self-contained warm air source.

Now referring more particularly to the drawing, there is shown therein, a vaporizer attachment for a vacuum cleaner comprising a cylindrical hollow housing 10 consisting of a base part 11 and a cover part 20 removably attached thereto.

In the preferred form the base and cover parts are made of molded plastic, either opaque or transparent, although a light weight metal, such as aluminum, might also be used. A plastic that is chemically inert is preferable, since such a material is more easily kept sanitary.

The base 11 has a continuous circular side wall 12 and a circular bottom wall 13. The side wall 12 has a plurality of spaced parallel slots or apertures 14 cut therethrough which serve as air vents or outlets.

Four bosses or pegs 15 are spaced equidistant apart at the outer edge of the side wall 12.

The cover 20 has a pair of concentric peripheral

2

flanges 22 and 23 extending perpendicularly therefrom, the said flanges being separated by a laterally extending shoulder 24. The inside diameter of the outer flange 23 being such that the flange 23 may be telescopically fitted over the open end of the base 11 with the outer edge of the side wall 12 between the concentric flanges 22 and 23 as shown in the Figures 1 and 2.

An inlet aperture 25 is located in the cover 20. An externally threaded sleeve 26 is formed integral with the cover 20 at the aperture 25.

Reference numeral 27 indicates an adapter to which a conventional vacuum cleaner blower hose can be attached. Various adapters 27 can be interchangeably mounted on the sleeve 26 at will to enable the device to be attached to vacuum cleaner hoses of any diameter or style or directly to the air outlet of a can-type vacuum cleaner as explained in my hereinabove mentioned co-pending application.

A bacteria and dust filter 29 composed of a loosely felted cellulose disk, such as is commonly used in tank type vacuum cleaners, is seated on the edge of the inner cover flange 22 and over the air inlet aperture 25 as shown in the Figures 1, 2 and 3. The diameter of the filter disk is such that its edges just touch the inner edge of the flange 23, the filter being held in place by a split locking ring 28. The ring 27 fits between the flanges 22 and 23 and is seated on the shoulder 24 on top of the peripheral edge of the filter disk 29.

Reference numeral 21 indicates L-shaped slots spaced equi-distant around the periphery of the cover 20 and adapted to receive the base pegs 15 in interlocked engagement when the cover flange 23 is telescopically fitted over the base 11 and twisted clockwise. At the same time, the telescopic edge of the base wall 12 bears against the filter locking ring 28 to press it against the edge of the filter 29 which is caught between the ring 28 and the shoulder 24 and held securely in place as shown in Figures 1 and 2.

The fluid reservoir 30 is intended to absorb and hold a germicidal liquid such as triethylene glycol. The reservoir is made of a highly absorbent material such as a natural or artificial sponge 32 which is contained in a loosely knitted fiber envelope 31, the sponge being a type of structure that retains its open porous frame even when holding the maximum amount of fluid. The contained fluid does not cause a matting or collapse of the supporting structure even when the structure is fully saturated. Furthermore the area of exposed surface remains constant under all degrees of saturation. The envelope 31 is of a size to substantially fill the housing 10 when stuffed with the sponge 32. The

envelope 31 is roughly square in shape with sufficient thickness to contact the base bottom wall 13 and the filter 29 when stuffed with the sponge 32 and nested within the housing as shown in Figure 2.

The bounding corners 33 rest against the side walls 12 and create a narrow passageway between the straight sides of the reservoir envelope and the side wall 12 so that the air blown into the housing is free to circulate around the reservoir and leave the housing in saturated condition through the apertures 14 as shown in the Figures 2 and 3.

The reservoir just described, will hold ten to twenty times the amount of liquid capable of being held by the vaporizer described in my co-pending application mentioned hereinbefore.

In operation the device is attached to the blower hose of a vacuum cleaner by means of the adapter 27. The reservoir 30 is saturated with triethylene glycol, or other suitable liquid, and the cover is attached to the base, as described hereinabove, and the vacuum cleaner set in operation.

Air blown through the inlet 25 passes through the filter disk 29 which removes all bacteria contaminated dust. The filtered air then flows through and around the reservoir 30 causing the triethylene glycol to evaporate. The vapor laden air then passes through the housing vents 14 and out into the room whose atmosphere is being conditioned.

The large surface area afforded by the sponge results in the more rapid evaporation of the liquid than is possible with a simple felted pad. Furthermore, the large size of the reservoir and its direct contact with the dust filter 29 creates sufficient obstruction to the free flow of the air entering through the aperture 25 to cause the heated air to intimately contact the reservoir surface and pick up the vapors efficiently and quickly.

The air is heated by the normal heating action of the operating vacuum cleaner motor, since the air sucked in by the conventional vacuum cleaner is usually passed over the motor to cool the motor before entering the bag, or in this case, the blower hose which takes the place of the bag.

The following test was made to illustrate the efficiency of the improved reservoir with its enlarged surface area.

The reservoir 30 was weighed before and after being saturated with 10% triethylene glycol. The device was attached to a vacuum cleaner and operated for 100 minutes. The reservoir was weighed at various intervals during the operation of the system and the following are the results:

Results

Time	Weight	Loss in Weight
	Grams	Grams
Reservoir alone	34	
Reservoir saturated	99.5	
After 10 minutes	67.3	32.2
After 25 minutes	47.3	20.0
After 45 minutes	43.4	3.9
After 60 minutes	43.0	0.4
After 80 minutes	42.5	0.5
After 100 minutes	42.3	0.2

Conclusion

The above results indicate that 32.2 grams of the liquid was vaporized from the saturated res-

ervoir during the first ten minutes of operation and that 52.2 grams of the liquid was vaporized during the first twenty-five minutes of operation.

Using a reservoir saturated with 50% triethylene glycol tests were run to determine the concentration of triethylene glycol liberated by this device after periods of 10 minutes, 20 minutes, 30 minutes and 50 minutes and also to determine the length of time the triethylene glycol remained in the air after the device had been shut off yielded the following results.

Results

Time of Run	Concentration of Triethylene Glycol	
	Mg/liter.	
10 minutes	.0035	
20 minutes	.0055	
30 minutes	.0070	
50 minutes	.0087	

Elapsed Time after Vacuum Cleaner had been turned off, following 50 minutes run	Concentration of Triethylene Glycol	
	Mg/liter.	
10 minutes	.0067	
20 minutes	.0050	
30 minutes	.0044	
50 minutes	.0028	

Conclusion

The above test indicates that the air in a room containing 1000 cubic feet was effectively germicidal within 20 minutes after the device, with the reservoir containing 50% triethylene glycol, was turned on. The room remained effectively germicidal for 20 minutes after the device had been turned off.

The rapid and efficient vaporization of the triethylene glycol evidenced by these tests is primarily due to the envelope type reservoir 30. The large surface area of the contained sponge material, together with the substantially square shape of the envelope provides intimate contact on five sides of the reservoir with the warm air from the vacuum cleaner.

In contrast the absorbent pad of my original vaporizer described in the above mentioned application, presented only one surface to the air entering the case. Furthermore, the bulk of the reservoir 30 makes it self-positioning within the hollow housing 10.

The present device is therefore economical of material and labor in its assembly, since no special positioning or retaining means are required. In addition to economy of manufacture, the improved device is reliable in operation since it is impossible to accidentally displace the reservoir once it is nested within the housing.

In the Figure 7 is seen an alternate manner of operating the device by means of a self-contained warm air source.

The device illustrated consists of a hollow sheet metal case 50 having inlet louvers 51 in the lower portion thereof. Reference numeral 52 indicates a shallow pan or first reservoir located within the case just below the louvers 51 and adapted to be filled with triethylene glycol.

A bonnet 53 is located centrally of the top of the case. A resistance wire coil 57 capable of generating heat when energized by an electric current is located within the bonnet 53. An air delivery stack 54 is mounted on the outlet end of

the bonnet 53 and the vaporizer unit 10 containing the sponge or second reservoir 30, described hereinabove, is mounted on the delivery stack by means of its adapter 27 as shown in the Figure 7.

Reference numeral 55 indicates an electric fan mounted within the case by means of the support bracket 56. The fan 55 is positioned above the inlet louvers 51 and below the bonnet 53 so that air is drawn into the case through the louvers and blown out of the case through the bonnet 53 and stack 54 upon rotation of the fan blades.

Tri-ethylene glycol is poured into the pan 52 and is also made to saturate the fluid reservoir 30 of the vaporizer 10.

The unit is plugged into an electrical outlet which causes the element 57 to heat and starts the fan 55. The air passing over the heated element 57 becomes hot and passes up through the stack 54 into the vaporizer 10. The air is filtered and upon hitting the second fluid reservoir 30 vaporizes the tri-ethylene glycol carrying it out into the atmosphere. The heating element 57 also warms the entire interior of the case and vaporizes the tri-ethylene glycol in the pan 52. This vapor is picked up by the pull of the fan 55 and it too is passed out through the stack 54 and vaporizer unit 10 after having its temperature elevated by passage through the heated bonnet to increase its vapor holding capacity before contacting the second reservoir or sponge 30. By effecting evaporation in two stages, accompanied by a rise in temperature, the efficiency of the device is greatly increased.

The structure illustrated in the Figure 7 may be used portably without requiring a vacuum cleaner. It has double vaporization power and it is small, economical and convenient to use.

It will now be clear that there is provided a device which accomplishes the objectives heretofore set forth. While the invention has been disclosed in a preferred and alternate form; it is to be understood that the specific embodiments thereof as described and illustrated herein are

not to be considered in a limited sense as there may be other forms or modifications of the invention which should also be construed within the scope of the appended claim.

5 I claim:

A liquid vaporizer, comprising in combination, a hollow case member having air inlet louvers proximate the lower portion thereof and a bonnet in the upper portion thereof including an air vent stack, a first reservoir for a volatile liquid located within the case member having its upper edge proximate the said inlet louvers, heating means located in the case member within the said bonnet, a fan mounted within the case member between the inlet louvers and the bonnet whereby air is drawn through the louvers and into the case over the first reservoir and blown out of the case through the bonnet and stack upon operation of the said fan, and a hollow housing mounted on the said stack, the said housing comprising a cover part and a complementary base part, the said cover part having an inlet aperture adapted to engage the upper end of said stack and receive warm air therefrom, the said base part having a plurality of outlet apertures in the wall thereof and a second reservoir for a volatile liquid, comprising a sponge, nested within the said hollow housing and substantially filling the same, the heating means operating to elevate the temperature of the air after it has passed over the first reservoir, to increase its vapor holding capacity before passage into the housing containing the second reservoir.

VINCENZO JAMES LEE.
